(57) **CLAIM**

The ornamental design for a table, as shown.

DESCRIPTION

FIG. 1 is a front perspective view of a table, according to one embodiment of this invention;

FIG. 2 is a top view of the table, as shown in FIG. 1;

FIG. 3 is a front view of the table, as shown in FIG. 1;

FIG. 4 is a back view of the table, as shown in FIG. 1;

FIG. 5 is a side view of the table, as shown in FIG. 1; and,

FIG. 6 is a bottom view of the table, as shown in FIG. 1.

The broken lines in the drawings are for illustrative purposes only and form no part of the claimed design.
